UNITED STATES PATENT OFFICE

GEORGE BENJAMINE SCHNEIDER AND ELSWORTH STROWBRIDGE NOWERY, OF BEAUMONT, TEXAS

WELL BOTTOM

Application filed July 5, 1929. Serial No. 376,198.

This invention relates to new and useful improvements in a well bottom.

One object of the invention is to provide a device of the character described specially designed for attachment to the lower end of a well screen and provided for controlling the flow of fluid, through said lower end.

Another object of the invention is to provide a device of the character described designed to be attached to the lower end of a well screen and embodying a sectional body having one or more back pressure valves therein and of such construction that the number of valves employed may be varied as desired.

A further feature of the invention resides in the provision of a device of the character described having a valve body with a novel type of back pressure valve therein, designed to permit the flow of fluid downwardly through the body and to prevent the back flow thereof, and equipped with a screen for protecting said valve and a safety plug for completely closing said body, when desired, to cut off all flow of fluid through said body.

With the above and other objects in view this invention has particular relation to certain novel features of construction, operation and arrangement of parts, an example of which is given in this specification and illustrated in the accompanying drawing, wherein:

Figure 1 shows a vertical sectional view of the device showing the wash pipe therein.

Figure 2 shows a side view of the device, partly in section, showing the safety plug therein, and

Figure 3 shows a fragmentary sectional view of a modified form thereof.

Referring now more particularly to the drawing wherein like numerals of reference designate similar parts in each of the figures, the numeral 1 designates a well screen to the lower end of which the device is to be attached and the numerals 2, 2 designate intermediate sections of the body. Any desired number of these sections may be employed depending on the number of back pressure valves desired. The sections 2 are similar, the upper end of each section being screwed

into the lower end of the section above and the outer surface of the assembled sections being flush. Attached to the lower end of the lower section 2 there is the conventional guide plug 3, whose outer surface is also flush with the adjacent section 2. Screwed unto the upper end of the upper section 2 there is the tubular top section 4 whose upper end is internally threaded to receive the reduced externally threaded lower end of the tubular nipple 5 into the upper end of which the lower end of the screen 1 is threaded. Within each section 2 there is screwed a valve cage as 6 which comprises the annular valve seat 7 and the depending spider 8, cage 6 like in form. Screwed with the coupling 4 there is a valve cage 9 embodying the annular seat 10 and the depending cage like spider 11. The cage 9 has an upstanding sleeve 12 into which the lower end of the tubular perforated screen 13 is screwed.

Associated with the respective seat 7, 10 are the similar downwardly opening valves 14 which have the upstanding wing-like guides 15 that work through the seats above. These valves are seated on the coil springs 16 which are confined within and supported by the corresponding valve spider. Each valve has a depending stem as 17 which fits within the upper end of the corresponding coil spring 16 and the lower ends of these springs surround the upper ends of the bolts 18 which are threaded through the lower ends of the corresponding spiders.

The valves 14 are thus held yieldingly against their corresponding seats but are permitted to open to permit fluid to pass downwardly through the body and out through the lower end of the guide plug 3.

Screwed within the upper end of the nipple 5 there is a bushing 19, having internal coarse threads and having an upwardly flared seat above said threads.

In use the device is attached to the lower end of the screen to be set in a well bore. When the screen is set it is usually necessary to wash said screen and in order to accomplish this, the wash pipe 20 is let down into the screen with its reduced lower end 21 fitting closely through the bushing 19 and

with its external shoulder 22 set on the flared seat 23 of said bushing. Water is then forced down through said wash pipe 20 and is excluded from passing outwardly through 5 said screen and is forced to pass on downwardly through said screen 13 opening said valves 14 and passing on out through the guide plug 3 and up around the well screen 1 to wash the same. The screen 13 prevents 10 clogging material from reaching the valves. When the well screen 1 is washed the oil or other fluid from the surrounding strata may then flow in through said well screen and up to the ground surface and the valves 14 will 15 prevent any unscreened fluid from passing up into the bottom of the screen 1. When an oil well has been completed and the screen 1 set and washed as above described and 20 production started it is essential that the fluid be excluded from passing into the well screen 1 except through the screen surface thereof and for that purpose a safety plug as 24 has been provided. This plug may be attached by left hand threads 25 to a string 25 of pipe and let down through the screen 1. The lower end of this plug has coarse right hand threads 26 which may be screwed into the bushing 19 and above said threads has an annular tapering seat 27 adapted to form 30 a tight joint with the seat 23. When this plug 24 has been screwed home the string of pipe through which it is manipulated may be detached by a continued turning to the right and it will be unscrewed from said plug 35 by reason of the left hand threads 25. The upper end of the plug 24 is hollow and has an inlet port 28 so that fluid can enter through said port and pass up through said plug into the string of pipe used for setting 40 the plug so as to permit said string to fill with water to prevent its collapsing from the pressure from the outside. This safety plug 24 will prevent inlet of fluid into the lower end of the well screen in case the valves 45 14 should for any reason be held open by clogging material.

In the form shown in Figure 3 the connecting nipple 5 and screen 13 are dispensed with the upwardly flared bell-shaped nipple 29 is 50 screwed in the upper end of the sleeve 12 and when it is desired to wash the screen as above stated the wash pipe 20 may be lowered into said nipple 29 and seated therein and the well screen then washed in the manner hereinabove stated.

Preferred forms of the invention have been 55 illustrated in the drawing and described in the specification by way of illustration only while the broad principle of the invention 60 will be defined by the appended claim.

What we claim is:

In a well bottom the combination with a 65 casing of an annular bushing fixed therein and having internal threads and an upwardly flared seat, a plug having threads on its

lower end adapted to intermesh with the threads of said bushing said plug being shaped to fit closely against said seat, the upper end of the plug being tubular and having a wall port, and also having external 70 threads pitched reversely with respect to the lower end threads.

In testimony whereof we have signed our names to this specification.

ELSWORTH STROWBRIDGE NOWERY. 75
GEORGE BENJAMINE SCHNEIDER.
